RIBBON SHIFT MECHANISM

Edward G. Watkins and James A. Dell, Gardner,
Mass., assignors to Simplex Time Recorder
Company, Gardner, Mass., a corporation of
Massachusetts

Application February 17, 1936, Serial No. 64,246

10 Claims. (Cl. 197—151)

This invention relates to ribbon shift mechanism capable of general application but particularly designed for use on workmen's time recorders.

5 The invention relates more particularly to that type of time recorder in which the time record is printed in figures on individual record cards and in which a two-color ribbon is used to differentiate between regular and irregular 10 registrations.

It is the general object of our invention to provide improved means for shifting the ribbon automatically from one color to the other at predetermined time intervals.

15 A further object is to provide means by which the ribbon shift may be accomplished with very slight additional load on the time mechanism.

Our invention further relates to arrangements and combinations of parts which will be hereinafter described and more particularly pointed out in the appended claims.

A preferred form of the invention is shown in the drawings, in which

Fig. 1 is a front elevation of our improved 25 ribbon-shift mechanism;

Fig. 2 is a partial front elevation but showing certain parts in a different position;

Fig. 3 is a side elevation of the timing mechanism;

30 Fig. 4 is a sectional plan view, taken along the line 4—4 in Fig. 1;

Fig. 5 is a detail sectional plan view, taken along the line 5—5 in Fig. 3;

Fig. 6 is a plan view of certain parts, looking 35 in the direction of the arrow 6 in Fig. 3;

Fig. 7 is a partial sectional side elevation, taken along the line 7—7 in Fig. 1;

Fig. 8 is a detail sectional plan view, taken along the line 8—8 in Fig. 3;

40 Fig. 9 is a side elevation of certain parts shown in Fig. 3 but in a different operative relation, and

Fig. 10 is a sectional side elevation, taken along the line 10—10 in Fig. 5.

45 Referring to Fig. 7, we have shown type wheels 10 mounted to rotate adjacent a card chute 11 in which a record card C may be inserted. A ribbon R is interposed between the type wheels 10 and the card C, and a hammer 12 is provided for striking a blow against the card, by which blow the card and ribbon are moved forcibly against the type on the type wheels 10, thereby producing a printed record on the card.

55 The ribbon R is mounted on spools S and S'

and is wound back and forth from one spool to the other in the usual manner by actuating devices not shown. For the purposes of this application it is sufficient to state that the upright shaft 14 (Fig. 1) is intermittently rotated from the hammer mechanism and that the shaft 14 is also shifted axially as the ribbon approaches one end or the other of its limit of travel.

5 Pinions 15 and 16 (Fig. 1) on the shaft 14 are thus alternately engaged with gears 17 and 18 on shafts 20 and 21 which support the spools S and S'. The spool shafts 20 and 21 are mounted to slide in frame members or side plates 22 and 24 which are rigidly secured to the frame of the time recorder.

10 Grooved collars 25 and 26 (Fig. 1) are secured to the spool shafts 20 and 21 respectively, and an auxiliary side plate 27 is mounted to slide on cross rods 28 and 29 fixed in the side plates 22 and 24. The upper and lower ends 20 of the auxiliary side plate 27 are notched to fit into the grooves of the collars 25 and 26, so that these collars and the shafts 20 and 21 on which they are mounted will be shifted axially when the side plate 27 is moved along the cross 25 rods 28 and 29.

15 Solenoid coils 30 and 31 (Figs. 1 and 4) are mounted on a casing 32 secured to the fixed side plate 22. A plunger 33 is secured at one end to the movable side plate 27 and extends through 30 the axially aligned coils 30 and 31.

The movable side plate 27 has an offset end portion 35 (Figs. 1 and 4) on which is mounted a ribbon guide plate 36 which extends across the front of the type wheels 10 and guides the 35 ribbon closely adjacent to but out of contact with said wheels. A shield 37 (Fig. 4) is secured by screws 38 to the front side of the ribbon guide 36 and is provided with a slot 39 through which the type to be printed are exposed. The shield 37 keeps the ribbon from 40 accidental contact with the card and prevents smudging of the record.

The extreme left-hand end of the ribbon guide 36 is bent rearward as indicated at 40 (Fig. 4) 45 and is slidably supported by a fixed stud 41 extending through an opening therein.

The parts thus far described constitute a slidably mounted ribbon carriage which may be shifted axially of the type wheels 10 at desired 50 intervals by energizing a solenoid coil 30 or 31.

The circuit-closing and releasing mechanism for effecting the desired shifting movements of the ribbon carriage will now be described.

Wires 44 and 45 (Fig. 3) connect one terminal 55

of each solenoid coil 30 and 31 to a line wire L, and wires 46 and 47 connect a second line wire L' to a pair of flat spring members 48 and 49 (Fig. 5) respectively. The spring member 48 has a movable contact 50 (Fig. 10) mounted at the lower side of its free end, and the spring member 49 has a contact 51 (Fig. 9) similarly mounted.

A plate 52 (Figs. 5 and 10) of hard rubber or similar insulating material is secured to the end of the flat spring member 48 and extends substantially outward therefrom. The flat spring member 49 (Fig. 9) similarly supports a rubber plate 53. At its extreme outer end, the rubber plate 52 is provided with a flat metal plate 54 projecting somewhat beyond the end of the plate 52, and the rubber plate 53 is similarly provided with a metal plate 55, all for a purpose to be described.

20 The second pair of terminals of the solenoid coils 30 and 31 are connected by wires 60 and 61 (Figs. 1 and 5) to contact plates 62 and 63 provided with fixed contacts 64 (Fig. 10) and 65 (Fig. 9) which are aligned with the movable contacts 50 and 51 previously described.

25 The flat spring members 48 and 49 and the contact plates 62 and 63 are all supported on a block 66 (Figs. 3 and 10) of hard rubber or similar material, which in turn is mounted on a fixed bracket 67. Another fixed bracket 68 (Figs. 3 and 9) supports a horizontal plate 69, preferably of insulating material, which forms a stop to limit upward movement of the rubber plates 52 and 53 and the metal plates 54 and 55 mounted thereon.

30 Trip levers 70 and 71 (Figs. 3 and 6) are loosely mounted on a fixed pivot stud 72 and are provided with upwardly offset cam portions 74 and 75. Coil springs 76 and 77 act to pull the right-hand ends of the trip levers downward, as viewed in Fig. 3, and this downward movement is limited by stop screws 78 and 79 in a fixed bracket or arm 80.

35 The trip lever 70 is provided with a depending link 81 (Fig. 10) pivoted thereto at 82, and the trip lever 71 is similarly provided with a depending link 83 (Fig. 9) pivoted at 84.

40 The link 83 is provided with an offset shoulder 85 adapted under certain conditions to engage the plate 55 associated with the flat spring member 49.

45 The lower end of the link 83 is pivoted at 86 to a horizontal link 87 (Figs. 3 and 8) which extends forward in the machine and is provided with a longitudinal slot 88 at its forward end. A headed stud 90 extends through the slot 88 and with the slot 88 provides a lost motion connection between the link 87 and a cross arm 91 mounted on a vertical rock shaft 92 (Figs. 1 and 3).

50 A coil spring 93 (Fig. 3) is connected to the link 83 and tends to move the defending link 83 and horizontal link 87 forward whenever such movement is permitted.

55 The lower end of the depending link 81 (Fig. 8) is similarly pivoted at 96 to a horizontal link 97 having a slot 98 in its forward end and connected by a stud 100 to the opposite end of the cross arm 91.

60 The depending link 81 (Fig. 10) is also provided with a shoulder 101 and with a coil spring 102, corresponding to the parts 85 and 93 previously described.

65 The rock shaft 92 is mounted in upper and lower fixed bearings 103 and 104 (Fig. 1) and

is provided at its upper end with a crank arm 105 having a radial slot 106 (Fig. 3) through which a screw or stud 107 extends into a bar 108 (Fig. 1) which is mounted on the movable ribbon carriage plate 27 previously described and which extends outwardly therefrom.

70 From these connections it will be obvious that sliding movement of the ribbon carriage will cause the shaft 92 to be oscillated and to move the links 87 and 97 in opposite directions, as indicated by the arrows in Fig. 8.

The timing means for actuating the trip levers 70 and 71 comprises a large timing disc 110 (Fig. 3) rotatably mounted on a fixed stud 111 and provided with external gear teeth meshing with a small drive pinion 113 mounted on a shaft 114 (Fig. 1) which is rotated by time mechanism (not shown) at such a speed that the disc 110 makes one revolution every twenty-four hours.

20 Two series of clips 117 and 118 are provided, and each of these clips has a stud 119 in one end fitting freely in any one of the holes 116, and also has a segmental slot 120 to receive a screw 121 to be inserted in a selected threaded hole 25 115.

25 At its outer end, each clip 117 has a stud 122 projecting outward from the clip and from the adjacent face of the timing disc 110. Each clip 118 is similarly provided with an outwardly projecting stud 124.

30 It will be seen from Fig. 3 that the studs 122 on the clips 117 are at a greater distance from the axis of the disc 110 than the studs 124 on the clips 118, and it will also be clear from Fig. 1 35 that the studs 122 are shorter than the studs 124. The outer trip lever 71 (Fig. 3) is bent upwardly as shown, so that the edge of the cam portion 75 is normally positioned higher than the corresponding edge of the cam portion 74 of the 40 lever 70.

35 The provision of the clip slots 120 for the screws 121 affords the clips a certain angular adjustment about their pivot studs 119, so that the studs 122 and 124 may be set at any desired 45 point in the entire twenty-four hour circumference.

40 Having described the details of construction of our improved ribbon shift mechanism, we will now describe the operation thereof.

45 In Fig. 2 the parts are set in the position to locate the left-hand half of the two-color ribbon in position for engagement by the type wheels 10 and this part of the ribbon may be assumed to be the blue half of the ribbon, used for 50 regular or full time records.

55 The parts will remain in this position until the timing disc 110 rotates sufficiently to bring the stud 124 of the clip 118 (mounted on the disc 110 at 7:00 A. M.) into contact with the cam portion 75 of the outer trip lever 71. Depression and subsequent release of the lever 71 momentarily closes the circuit through the contacts 51 and 65 and through the wire 61 and the solenoid 31, shifting the ribbon carriage to the left to the 60 position shown in Figs. 1 and 4, and bringing the right-hand or red part of the ribbon in position for engagement by the type wheels 10 to indicate late or irregular records.

65 The detailed operation of the connections between the trip lever 71 and the solenoid 31 is as follows:

70 When the stud 124 of a clip 118 engages the cam portion 75 of the trip lever 71 and depresses the same, the right-hand end of the lever 71 is 75

swung upward to the position shown in Fig. 9 against the tension of the spring 77, and the shoulder 85 of the link 83 snaps past the edge of the plate 55 and assumes a position overlapping the edge of the plate.

No further action takes place until the stud 124 passes beyond the sharp edge of the cam portion 75 of the trip lever 71 and allows the spring 77 to return the lever to its original position, shown in Fig. 3.

During the accompanying downward movement of the link 83, the shoulder 85 engages the plate 55 and depresses the contact 51 into engagement with the fixed contact 65, thus completing the circuit through the wire 61 and the solenoid 31. The solenoid immediately actuates the plunger 33 to move the ribbon carriage from the right-hand position shown in Fig. 2 to the left-hand position shown in Fig. 1.

This sliding movement of the carriage is effective through the bar 108 (Fig. 1) to rock the crank arm 105 and turn the vertical shaft 92 and cross arm 91 in the direction of the arrow *a* in Fig. 8.

During the first part of this movement, the stud 90 (Fig. 8) slides freely rearward along the slot 88 in the link 87, but as the movement approaches completion, the stud 90 strikes the end of the slot, driving the link 87 rearward, and correspondingly swinging the depending link 83 rearward sufficiently to release the edge of the plate 55, whereupon the spring plate 49 snaps upward, breaking the solenoid circuit through the contacts 51 and 65.

The described movement of the upright shaft 92 and cross arm 93 is also operative to move the stud 100 to the intermediate position shown in Fig. 8, in which position the link 81 is free to be moved forward by the spring 102 (Fig. 10) into operative position with respect to the edge of the plate 101, as shown in Figs. 5 and 10.

When the clip 117 (which is shown attached to the disc 110 at 12:00 noon) has been rotated to a position in which its stud 122 engages the cam portion 74 of the trip lever 70, the lever 70 will be thereupon depressed and afterwards released, and will operate in a precisely similar manner to energize the solenoid coil 30 and return the ribbon carriage to the initial or right-hand regular position shown in Fig. 2. Such movement swings the shaft 92 and cross arm 91 in a direction opposite to the arrow *a* in Fig. 8, moving the horizontal link 97 and depending link 81 rearward, and breaking the circuit for the solenoid 30.

The studs 124 in the clips 118 are too near the axis of the disc 110 to engage the trip lever 70, and the studs 122 in the clips 117 are too short to engage the trip lever 71. Each set of clips and studs thus operates only with its own trip lever.

From the preceding description it will be evident that the power for shifting the ribbon carriage is derived entirely from the solenoid coils 30 and 31, and that the time mechanism simply rotates the timing disc 110 very slowly to bring the studs 122 and 124 respectively and alternately into engagement with the trip levers 70 and 71.

Our improved ribbon shift mechanism has proved reliable and satisfactory in service and has relatively few working parts.

Having thus described our invention and the advantages thereof, we do not wish to be limited to the details herein disclosed, otherwise

than as set forth in the claims, but what we claim is:—

1. In a time recorder, ribbon shift mechanism comprising a slideable ribbon carriage, electro-magnetic means to shift said carriage in one direction, means to return said carriage, and automatic means for rendering said electro-magnetic means operative and said return means operative in fixed alternation.

2. In a time recorder, ribbon shift mechanism comprising a slideable ribbon carriage, electro-magnetic means to shift said carriage in one direction, a circuit for said means, means to thereafter return said carriage, a disc, mechanism to rotate said disc, adjustable devices on said disc effective to cause the closing of the electro-magnetic circuit, and additional adjustable devices on said disc effective to render said return means operative.

3. In a time recorder, ribbon shift mechanism comprising a slideable ribbon carriage, electro-magnetic means to shift said carriage in one direction, a circuit therefor, means to return said carriage, automatic means for rendering said electro-magnetic means operative and for thereafter rendering said return means operative, and connections through which movement of said carriage by said electro-magnetic means breaks the electro-magnetic circuit.

4. In a time recorder, ribbon shift mechanism comprising a slideable ribbon carriage, separate electro-magnetic means to shift said carriage in each direction, and automatic means for rendering said separate electro-magnetic means operative in fixed alternation.

5. In a time recorder, ribbon shift mechanism comprising a slideable ribbon carriage, separate electro-magnetic means to shift said carriage in each direction, a disc, mechanism to rotate said disc, adjustable devices on said disc effective to cause the closing of one electro-magnetic circuit, and additional adjustable devices on said disc effective to cause the closing of the other electro-magnetic circuit, said devices and said additional devices being effective to close said circuits alternately.

6. In a time recorder, ribbon shift mechanism comprising a slideable ribbon carriage, separate electro-magnetic means to shift said carriage in each direction, a circuit therefor, automatic means for selectively rendering said electro-magnetic means alternately operative, and connections through which completion of the resultant carriage movement breaks the electro-magnetic circuit which was closed.

7. In a time recorder, ribbon shift mechanism comprising a slideable ribbon carriage, separate electro-magnetic means to shift said carriage in each direction, a circuit for each electro-magnetic means, automatic means for rendering said electro-magnetic means operative in fixed alternation, and means to break each circuit before the other circuit can be automatically closed.

8. In a time recorder, a ribbon carriage, electro-magnetic means to shift said carriage in one direction, electro-magnetic means to shift said carriage in the opposite direction, a disc, two series of circuit-controlling members on said disc, one series controlling the electro-magnetic means which shifts said carriage in one direction and the other series controlling the electro-magnetic means which shifts said carriage in the opposite direction, and means to rotate said disc.

9. In a time recorder, ribbon shift mechanism comprising a slideable ribbon carriage, separate

electro-magnetic means to shift said carriage in each direction, a separate circuit for each electro-magnetic means, a separate contact device in each circuit, automatic means for selectively closing said contact devices in fixed alternation, and connections through which completion of the resultant carriage movement opens the contact device in the electro-magnetic circuit which was closed to effect such movement and simultaneously renders said automatic means available for subsequent automatic closing of the contact device in the other circuit.

10. In a time recorder, ribbon shift mechanism comprising a slideable ribbon carriage, sepa-

rate electro-magnetic means to shift said carriage in each direction, a circuit for each electro-magnetic means, automatic means for closing said circuits in fixed alternation to render said electro-magnetic means alternately operative, and means to break each circuit before the other circuit is closed and to thereafter break said closed circuit as the resultant carriage movement is completed and to simultaneously render said automatic means available for subsequent automatic closing of the circuit previously broken.

EDWARD G. WATKINS.
JAMES A. DELL.
